DESIGN FOR A COMBINED WATER AND ICE BAG

Raymond W. Albright, Akron, Ohio, assignor to
American Anode Inc., Akron, Ohio, a corpora-
tion of Delaware

Application May 31, 1939, Serial No. 85,270

Term of patent 14 years

To all whom it may concern:

Be it known that I, Raymond W. Albright, a citizen of the United States, residing at Akron, in the county of Summit and State of Ohio, have invented a new, original, and ornamental Design for a Combined Water and Ice Bag, of which the following is a specification, reference being had to the accompanying drawing, forming a part thereof.

In the drawing,

Fig. 1 is a front perspective view of a combined water and ice bag embodying my new design;

Fig. 2 is a rear-perspective view of the bag of Fig. 1; and

Fig. 3 is a side elevation of the bag of Fig. 1.

I claim:

The ornamental design for a combined water and ice bag, as shown.

RAYMOND W. ALBRIGHT.
